HEEL PLATE
George J. Cyr, Jr.
Application February 10
7 Claims.

The invention relates to a heel plate that may be stamped of sheet aluminum, sheet zinc, sheet steel, sheet steel alloy or any other sheet metal or alloy, leather or whatever fabric or composition may be found suitable for a stamped heel plate or which may be cast out of any of the above described metals or any fabric or any plastic composition suitable for a cast heel plate. The purpose of the heel plate is to provide a means of enabling ordinary low hitch ski bindings not only to hold the ski to the ski boot but to keep the heel of the ski boot bound down to the ski. This is accomplished by providing a concave groove in the heel plate on the counter of the boot and at a point one-half inch or more higher up than the usual concave groove in the heel of the conventional ski boot. Thus, with the same harness and ski boots two or more optional positions for the adjustment of ski bindings, springs, straps or cables or other bindings are possible. The placing of the ski bindings in the upper groove increases the tension of the diagonal pull of the boot toward the ski and thus holds the heel more firmly on the ski.

25 Other incidental objects of the invention will hereinafter appear in the progress of the disclosure and as pointed out in the appended claims.

Accompanying this specification is a drawing showing a preferred form of the invention where-
30 in corresponding reference characters designate corresponding parts throughout the several views and wherein:

Figure 1 is a side elevational view of a portion of a ski boot hitched to a ski, showing the attachment plate secured to the heel portion of the boot.

Figure 2 is a bottom plan view of the attachment plate per se.

Figure 3 is a sectional view of Figure 2 through the plane 3—3 thereof.

In accordance with the invention and the preferred form thereof shown in the drawing, numeral 10 indicates the ordinary ski boot secured to a conventional ski 11 and is provided with a ski binding 12 of any known variety engaging a guide or groove on a heel plate mounted to the heel portion of the boot 10. The said heel plate is preferably comprised of a counter member having side walls 14 connected by a rear wall 15, the upper edges of the said side walls preferably tapering upwardly toward the upper edge of the rear wall. A protrusion 16 is secured to or formed on the outer surface of the counter member to engage ski binding 12 whereby the said ski binding is directed and maintained in an

PATENT OFFICE

1969 **FOR SKIING** **Manchester, N. H.**
1937, Serial No. 126,060 **Cl. 36—2.5**

angular position relative to the plane of ski 11. The said protrusion 16 forms the equivalent of a groove 20 in association with the counter member and is preferably disposed along the outer surface of the walls of the counter member at an angle such that the rear region of the formed groove 20 is elevated above the plane of grooved heel 21. 5

An inwardly turned attaching flange 17 extends off the lower edges of the walls of the counter member and is provided with a cross member 18 secured across the forward ends of the flange 17. Thus flange 17 and cross member 18 assume the contour of the lower side of boot heel 21. Moreover, flange 17 is provided with a group of openings 19 for suitably securing the heel plate to the ski boot 10.

The heel plate above described may be built into ski boot 10 while in the process of manufacture by inserting the heel plate between the heel seat or sole 22 and the upper of the boot and fastening the plate to the upper by any means such as screws, nails, rivets, burrs, plastic or cement. To apply the heel plate to an already manufactured ski boot, heel 21 is removed and the attaching flange 17 and cross member 18 are secured to the sole 22 of boot 10 by screws, nails, rivets, burrs, plastic or cement. Thereafter heel 21 is refastened to the sole 22. In order to mount the heel plate directly on the heel of a ski boot, the plate is merely fitted thereover and secured in place by any of the means known in the art.

It is understood that the heel plate may be made in all styles and sizes corresponding to the size and make of the ski boots and that other minor variations in material, shape and size of the parts, integration and location thereof may all be resorted to without departing from the spirit of the invention and without departing from the scope of the appended claims. 35 40

I claim:—

1. A heel plate for the heel portion of a ski boot to engage a ski binding thereat comprising a counter member engaging the counter portion of the ski boot, the said counter member having inclined guiding means to engage the ski binding and an inwardly turned flange for securing the plate to the heel of the boot. 45
  2. A heel plate for the heel portion of a ski boot to engage a ski binding thereat comprising a counter member engaging the counter portion of the ski boot, the said counter member having guiding means to engage the ski binding at an angle, and an attaching flange affixed to the 50 55

counter for securing the plate to the heel of the boot.

3. A heel plate for the heel portion of a ski boot to engage a ski binding thereat comprising 5 a counter member engaging the counter portion of the ski boot, the said counter member having peripheral guiding means to engage the ski binding at an angle, and an attaching member for securing the plate between the heel seat and the 10 heel of the boot.

4. A heel plate for the heel portion of a ski boot to engage a ski binding thereat comprising 15 a counter member engaging the counter portion of the ski boot, the said counter member having peripheral guiding means to engage the ski binding at an angle, and an attaching member for securing the plate beneath the heel of the boot.

5. A heel plate for the heel portion of a ski boot to engage a ski binding thereat comprising 20 a counter member having side and rear walls tapering upwardly and rearwardly, the said counter member fitting the counter of the shoe, peripheral guiding means on the said rear and side walls angularly disposed to engage the ski

binding, and an attaching flange affixed to the counter for securing the plate to the heel of the boot.

6. A heel plate for the heel portion of a ski boot to engage a ski binding thereat comprising 5 a counter member engaging the counter portion of the ski boot, the said counter member having peripheral guiding means to engage the ski binding at an angle, the highest point of the said guiding means being above the sole portion of 10 the boot, and an attaching member for securing the plate between the heel seat of the sole and the heel of the boot.

7. A heel plate for the heel portion of a ski boot to engage a ski binding thereat comprising 15 a counter member engaging the counter portion of the ski boot, the said counter member having peripheral guiding means to engage the ski binding at an angle, the highest point of the said guiding means being above the sole 20 portion of the boot, and an attaching flange affixed to the counter for securing the plate to the heel of the boot.

GEORGE J. CYR, JR.
